APPARATUS FOR GRAPHING THE
ELASTICITY OF BOWS

John E. James, Kankakee, Ill.

Application June 3, 1947, Serial No. 752,147

4 Claims. (Cl. 33—172)

1

This invention relates to an apparatus for graphing the elasticity of bows, and has as its primary object the provision of a mechanical member adapted to represent graphically the relative strength and weakness of all portions of a bow rim when under strain.

As conducive to a clearer understanding of this invention, it may here be pointed out that in the manufacture of bows, a necessary element of construction lies in the proper shaping and fashioning of the bow in order to distribute the strain on the material used proportionately throughout the flexing sections of the two bow limbs. Heretofore, this has been done by hand, and the result has been based largely on the skill of the bowyer. Various expedients have been utilized, including the taking of stress measurements and the computing of numerical data, but these expedients have been uniformly inaccurate, incomplete, and relatively time-consuming. A primary object of this invention is the provision of a device adapted to be passed along the bow limbs, and during such passage to record graphically the weak and stiff sections over every point of each bow limb, in order to permit relative adjustment of discrepancies, and insure equalization of strain distribution in desired proportions.

A further object of the invention is the provision of a device of this character which is sturdy and durable in construction, simple and inexpensive to manufacture, relatively easy to utilize, and extremely accurate in results.

Still other objects reside in the combinations of elements, arrangements of parts, and features of construction, all as will be more fully pointed out hereinafter and disclosed in the accompanying drawings, wherein there is shown a preferred embodiment of this inventive concept.

In the drawings:

Figure 1 is a top plan view of one form of device embodying features of the instant invention.

Figure 2 is a side elevational view of the construction shown in Figure 1, certain concealed portions thereof being indicated in dotted lines.

Figure 3 is a rear elevational view of the construction shown in Figures 1 and 2, as viewed from the left.

Figure 4 is a perspective view of a constructional detail.

Figure 5 is a perspective view of an additional constructional element.

Similar reference characters refer to similar parts throughout the several views of the drawings.

Referring now to the drawings in detail, the

2

device of the instant invention comprises a body portion generally indicated at 10, and comprised of two separable halves, each including a longitudinally extending base member 11, provided at its rearward end with a depending flange 12, and adjacent its rear end with a foot 13. Extending upwardly from each base portion 11 adjacent its rearward end is an inwardly curving arcuate member 14, the juncture of the two members forming an enlarged boss 15, provided with a bore for the reception of a pivot pin 16, the purpose of which will be more fully described hereinafter. Forwardly of the boss 15, the sections merge into a longitudinally extending handle grip member 17, the handle portion terminating in outwardly flared members 18, which extend downwardly to the base member 11. An arcuate guide bar 19 connects the extremities of the flared lower member 18.

20 An enlarged boss 20 adjacent the rearward end of the frame members 11 and below the boss 15 of the handle portion 17 carries a pivot 20' against which is seated one end of a sleeve 21, the opposite end of which is secured by the pointed end 22 of pivot screw 16. The sleeve 21 forms the pivot for a bell crank member 25, the extremity of which is provided with a sleeve 26 for the accommodation of a pencil 27, or the like, adapted to be biased downwardly therein, as by means of a rubber band 28, or the like. Also mounted on the sleeve 21 is an adjusting member generally indicated at 30, and including an apertured boss 31 through the aperture in which the sleeve 21 is adapted to pass, an extending arm 32 and an arcuate portion 33 provided on its inner face with a plurality of notches 34. The notches 34 are adapted to be selectively engaged by a stud 35 carried by the bell crank lever 25 and provided with a nut 26.

40 The leg 40 of bell crank member 25 beyond the pivot 21 is provided with an aperture 41 adapted to have secured thereto one end of a coil spring 42, the opposite end of which is suitably secured to a pin 43 carried by the frame 10. The extremity of the portion 32 of member 30 beyond the boss 31 is inwardly turned in substantial alignment with the arcuate portion 35, as indicated at 45, and is adapted to abut a shoe 46 having an arcuate surface carried by a bell crank lever 47, pivotally connected, as by a pivot 48, to the portion 12 of frame 10. The extremity of the member 47 beyond the pivot 48 carries a transversely extending roller 49, to one extremity of which is secured a spring 50, the opposite end being secured to a pin 51 carried by the frame

member 11. The upper extremity of the member 47 includes a horizontal portion 52 adapted to carry the shoe 46, as best shown in Figures 1 and 3.

It will now be seen that pressure imparted to the roller 49 will be transmitted to the shoe 46, and thence through the projecting member 45 and the notches 34 in the arcuate member 33 to member 25, vertical movement of the roller resulting in arcuate movement of the member 25, and consequently corresponding movement of the associated sleeve 26 and the pencil 27 carried thereby. Such movement of the pencil is indicated on a sheet of paper 60 carried by a plate 61 comprising the extremity of a channeled sheath 62 including inwardly turned, upper flanges 63 adapted for the support of an elongated strip 60 of graph paper.

Supporting means are provided for the device, and take the form of U-shaped members 64 and 65, including parallel bars, the upper extremities of the legs of the U being suitably secured between the portions 12 and the portions 13 of the frame members 11, respectively.

A vertically extending guide plate 66 is adapted to be secured to the forward extremity of the side member 11 which carries bell crank member 47, and a projecting member 67 is secured to the rear end of the device, the extremity thereof being in substantial alignment with the guide bar 66.

Extending guide plate 68 and member 67 can be changed from one side of the apparatus to the other to good advantage to accommodate right or left hand uses.

In the use and operation of the device, the bow is adapted first to be positioned on a tiller board, which, it may here be pointed out, is a vertically positioned backboard customarily utilized by bowyers upon which the bow is adapted to be clamped. In the operation of the device, the bow is clamped about an inch away from the board in unstressed position, a suitable sheet of graph paper inserted in the holder 62, and pinned to the center of the bow, and the device moved longitudinally of the bow 88. Obviously, any deviations in the surface of the bow will be registered in the manner previously described by movement of the roller 49, and corresponding movement of the pencil 27 over the graph paper. The procedure may be repeated with both bow limbs, and an accurate graph line of the configuration of the bow in unstressed position obtained. Subsequent to this operation, tension is applied to the bow, and the procedure repeated. It will be readily apparent that the second graph will follow closely the contour of the first up to the point where the true bend of the bow limb begins, whereupon deviation will occur, but such deviation will follow in general the contour of the first graph, provided the strain is proportionate throughout the length of the bow limb. Exceptionally weak or strong points will be marked by deviation in the graph line, and the exact position of such point may be determined by correlating the beginning of the graph line, as indicated by the pencil, with the exact position of the roller 49 on the bow limb, whereupon such deviations may be readily corrected in the customary manner.

From the foregoing it will now be seen that there is herein provided an improved device of this character which accomplishes all the objects of this invention, and others, including many practical advantages. It will further be

obvious that a graphic representation of the entire surface of the bow may be readily obtained with a minimum of time, effort and difficulty.

As many embodiments may be made of this inventive concept, and as many modifications may be made in the embodiment hereinbefore shown and described, it is to be understood that all matter herein is to be interpreted merely as illustrative and not in a limiting sense.

10 I claim:

1. In a device of the character described, a frame having side flanges and adapted to receive graph paper between the flanges, a vertically swinging bell crank lever pivotally mounted upon the frame and including upper and lower arms, a transverse roller secured to the lower arm and arranged beneath the frame for contact with a surface over which the frame is passed, a horizontally swinging lever pivotally mounted upon the frame, a spring connected with one end of the horizontally swinging lever, an adjusting element mounted upon the pivot of the horizontally swinging lever and having a laterally extending crank engaged and moved by a part of the vertically swinging bell crank lever and having an arcuate portion, adjustable means carried by the horizontally swinging lever for securing the arcuate portion to such lever, and a marking device carried by the free end of the horizontally swinging lever.

20 2. In a device of the character described, a frame having side flanges and adapted to receive graph paper between the flanges, a vertically swinging bell crank lever pivotally mounted upon the frame and including upper and lower arms, a roller secured to the lower arm to contact with a surface over which the frame is passed, a horizontally swinging lever pivotally mounted upon the frame, a spring connected with one end of the horizontally swinging lever to move it in one direction, an adjusting element mounted upon the pivot of the horizontally swinging lever and having a crank engaged and moved by a part of the vertically swinging bell crank lever and having an arcuate portion provided with spaced notches,

30 35 40 45 50 55 60 65 70 a stud mounted upon the horizontally swinging lever to engage within a selected notch of the arcuate portion, and a marking device carried by the free end of the horizontally swinging lever.

3. In a device of the character described, a frame having side flanges and adapted to receive graph paper between the flanges, a vertically swinging bell crank lever pivotally mounted upon the frame and including upper and lower arms, the lower arm having a part to contact with the surface over which the frame is passed, a horizontally swinging lever, a vertical sleeve secured to the lever between its ends, pivot elements mounted upon the frame and engaging within the opposite ends of the sleeve, a spring connected with one end of the horizontally swinging lever to move it in one direction, a horizontally adjustable element mounted upon the vertical sleeve and having a crank engaged and moved by a part of the vertically swinging bell crank lever and an arcuate portion having spaced notches, a stud carried by the horizontally swinging lever and engaging within a selected notch, and a marking device carried by the free end of the horizontally swinging lever.

4. In a device of the character described, a frame having side flanges and adapted to receive graph paper between the flanges, a vertically swinging bell crank lever disposed upon the exterior of the frame and pivotally mounted upon the side thereof and including upper and lower

75

arms, a transverse roller carried by the lower arm to contact with the surface over which the frame is passed, a transverse extension carried by the upper arm, a horizontally swinging bell crank lever, a horizontally swinging adjusting element including a laterally extending crank and an arcuate portion having spaced notches, common pivot means for the horizontally swinging bell crank lever and the adjusting element secured to the frame, a stud carried by the horizontally swinging bell crank lever and engaging in a selected notch of the arcuate portion, a shoe carried by the transverse extension of the vertically swinging bell crank lever and engaging the crank of

the horizontally swinging bell crank lever, a spring to swing the horizontally swinging bell crank lever in one direction, and a marking device carried by the horizontally swinging bell crank lever.
